UNITED STATES PATENT OFFICE

154,817

DESIGN FOR A TELEVISION RECEIVER

Carl J. Steinke, Chicago, Ill., assignor to Zenith
Radio Corporation, a corporation of Illinois

Application October 14, 1948, Serial No. 149,114

Term of patent 7 years

(Cl. D56—4)

To all whom it may concern:

Be it known that Carl J. Steinke, a citizen of the United States, residing at Chicago, in the county of Cook and State of Illinois, has invented a new, original, and ornamental Design for a Television Receiver, of which the following is a specification, reference being made to the accompanying drawing, forming a part thereof.

The figure shown is a perspective view, showing the front, and side of the television receiver.

The other side is the same as the side shown, and the rear is plain.

I claim:

The ornamental design for a television receiver, substantially as shown and described.

CARL JOHN STEINKE.
